UNITED STATES PATENT OFFICE.

KOMANOSUKE TOGAMI, OF FUKUOKA, JAPAN.

HYDRAULIC GASTRIC EXAMINER OR HYDRAULIC STOMACH-EXAMINING APPARATUS.

1,390,844.

Specification of Letters Patent. Patented Sept. 13, 1921.

Application filed February 17, 1919. Serial No. 277,694.

To all whom it may concern:

Be it known that I, KOMANOSUKE TOGAMI, a subject of the Emperor of Japan, and resident of 63 Kyuyanagimachi at the city 5 of Fukuoka, in the Prefecture of Fukuoka and Empire of Japan, have invented a new and useful Hydraulic Gastric Examiner or Hydraulic Stomach-Examining Apparatus, of which the following is a specification.

10 This invention relates to improvements in hydraulic gastric examiners or hydraulic stomach examining apparatus wherein a closed liquid vessel and an open liquid vessel are disposed in a row on a higher stage, 15 and the closed vessel is provided at the lower bottom with a discharge pipe to change the atmospheric pressure within as desired and made to communicate with a closed vessel to be connected with a gastric catheter by extending an air pipe jointed to the head of the first-mentioned closed vessel and inserting the extended end of the pipe into the latter closed vessel, and the open vessel is fitted at the bottom with a discharge pipe to make 20 25 the same communicate with the gastric catheter either directly or indirectly, all these parts being so arranged and constructed that there is produced difference in pressure between the interior of the stomach and 30 either of the said two closed vessels.

An object of this invention is to provide a hydraulic gastric examiner or stomach examining apparatus calculated to render the process of taking gas or liquid out of a 35 stomach surer and speedier.

Another object of this invention is to provide a hydraulic gastric examiner or stomach examining apparatus adapted to introduce any gas into the stomach and to survey 40 any change in gastric capacity most minutely and safely according to an increase or decrease in the atmospheric pressure within the stomach.

A further object of this invention is to 45 provide a hydraulic gastric examiner or stomach examining apparatus capable of increasing the usefulness of the gastric catheter by rendering its use more convenient, much safer, and considerably easier through 50 the various functions of its own.

Other objects and advantages to be derived from the use of this invention will appear in the following detailed description and the claims taken with an inspection of

the accompanying drawing which is a slant 55 view of the entire apparatus of this invention and wherein similar numerals and letters for reference designate like and corresponding parts.

In the accompanying drawing, 1 represents a closed glass vessel, having a capacity of about three thousand grams, provided at the lower part with a discharge pipe 3 and a cock 3' and fitted at the upper part with a bent pipe 5 which connects this vessel with 60 a closed vessel 6 arranged on the lower stage, and a branch pipe 5' is provided at a suitable part of the bent pipe 5 to make the same communicate with an air gage A. The closed vessel 6 is fitted at the lower part with a discharge pipe 9 and a cock 9' and provided at the upper part with a connecting pipe 6' which connects the same with the head of a closed vessel 7. The closed vessel 7 is fitted at the lower part with a discharge pipe 10 and a cock 10' and provided at the upper part with a connecting pipe 7' which causes 70 75 the same to communicate with an air gage B, a joint pipe 8 being arranged at another part of the vessel as shown. An open vessel 2 having a capacity of about four thousand grams, arranged on a level with the closed vessel 1, is provided at the lower part with a discharge pipe 4 and a cock 4', this pipe being connected in a T-shape with a connecting pipe 11 of an elevating vessel 12. And the connecting pipe 11 is fitted with a cock 11', and its farther end is connected with a cock 13' of a communicating pipe 13. 80 85

The cocks 3', 9', 10', 11', and 13' are, 90 respectively, closed and the closed vessel 1 is filled with fresh water and the open vessel 2 is filled with some suitable wash or lotion as a first step, and then the apparatus is operated in various ways according to the objects in view. For convenience, these ways are termed as the first operation, the second operation, and the third operation, thus:

The first operation: To take gastric juice out of the stomach, the joint pipe 8 is connected with a gastric catheter in the patient's mouth, and then the cock 3' is opened, whereupon the water in the closed vessel 1 is discharged through the discharge pipe 3 and the atmospheric pressure within the vessel is 100 reduced, with the consequence that low pressure is produced in the closed vessel 6 and the closed vessel 7 connected therewith 105

through the bent pipe 5, and the fluid in the stomach is completely sucked up into the vessel 7, going farther into the vessel 6 in case the vessel 7 is full of liquid. And, since 5 volumetric lines or gradations are provided at the outer surface of these two vessels, the volume of the contents can be readily told thereby. By this same method, the gas or gases in the patient's stomach may be taken 10 out, and in this case the volume of the gas or gases may be calculated from the degree of the lowering of the water-level in the closed vessel 1. As a different way of taking the 15 gas, the bent pipe 5 is closed after filling the closed vessels 6 and 7, the farther end of the joint pipe 8 is connected with the catheter, and the water is discharged by opening the discharge pipe 10, which renders it possible to draw the gas in the stomach up into the 20 closed vessel 7. In all the above-mentioned methods, atmospheric pressure is to be computed by referring to the air gage B.

The second operation: To introduce air or some other gas into the stomach, the joint 25 pipe 8 is connected with the gastric catheter after filling the closed vessels with air, the discharge pipe 9 is connected with the communicating pipe 13, and the liquid in the vessel 2 is run down while closing the bent 30 pipe 5 and the cocks 10' and 11', and as a result the air in the closed vessels 6 and 7 is introduced into the stomach, the pressure being exactly told by the air gage B.

The third operation: To wash or cleanse 35 the stomach, the communicating pipe 13 is connected with the gastric catheter, and the cocks 4', 11', and 13' are opened, and the liquid in the vessel 2 runs out to the elevating vessel 12. When the elevating vessel is 40 lifted higher than the position of the patient's body, the liquid contained in the elevating vessel flows out into the stomach, the liquid running out of the stomach again when the vessel is lowered below the said 45 body. Lastly, to completely remove the remaining liquid in the stomach, the same method as mentioned in the above first operation is to be used.

In short, this apparatus is based on the 50 well-known principle of hydraulic pressure, and renders it possible to ascertain pathological changes of the stomach, hitherto deemed exceedingly difficult and uncertain with percussion or palpation, most precisely

and minutely besides making it practicable 55 to examine stomach conditions without the least harm to the patient, which features entitle the apparatus to be called as a new and useful invention by way of examination and treatment of stomach diseases. 60

Having thus fully described my invention, what I claim as new and desire to secure by Letters Patent is:

1. In a hydraulic gastric examining apparatus comprising a stand provided with 65 superposed steps, a closed and an open vessel supported on the top step for receiving water and a wash lotion respectively, a discharge pipe and control valve therefor connected to each of said vessels, a pair of 70 closed connected vessels supported on the lower step and communicating with the upper vessels whereby low pressure is produced in the connected vessels when the water is discharged from the upper closed 75 vessel reducing the atmospheric pressure therein and a closed pipe having a gastric catheter communicating with one of said lower closed vessels for removing the gastric juice from the stomach of the patient as 80 the water is discharged from the upper closed vessel.

2. In a hydraulic gastric examining apparatus comprising a stand provided with 85 superposed steps, a closed and an open vessel supported on the top step for receiving water and a wash lotion respectively, a discharge pipe and control valve therefor connected to each of said vessels, a pair of 90 closed, graduated, connected vessels supported on the lower step and communicating with the upper vessels whereby low pressure is produced in the connected vessels when the water is discharged from the upper closed vessel reducing the atmospheric pressure 95 therein, air gages interposed between the upper and closed vessels for determining the atmospheric pressure in said vessels during the discharge of the water, a joint pipe having a gastric catheter communicating 100 with one of said lower closed vessels for removing gastric juice from the stomach of the patient by reducing the atmospheric pressure in said upper closed vessel.

In testimony whereof I affix my signature 105 hereto.

KOMANOSUKE TOGAMI.
